(57) **CLAIM**

The ornamental design for a wick assembly as shown.

DESCRIPTION

FIG. 1 is a front, top left perspective of a wick assembly, showing the new design;

FIG. 2 is a front, top, right perspective view thereof;

FIG. 3 is a front, bottom, left perspective bottom right view thereof;

FIG. 4 is a front, bottom, right perspective bottom right view thereof;

FIG. 5 is a rear, top left perspective view thereof;

FIG. 6 is a rear, top right perspective view thereof;

FIG. 7 is a top view thereof;

FIG. 8 is a bottom view thereof;

FIG. 9 is a left view thereof;

FIG. 10 is a right view thereof;

FIG. 11 is a front view thereof; and,

FIG. 12 is a rear view thereof.

The broken lines in the figures show portions of the wick assembly that form no part of the claimed design.
